UNITED STATES PATENT OFFICE.

LIPA POLINKOWSKY, OF ANTWERP, BELGIUM, ASSIGNOR TO WESTERN ELECTRIC COMPANY, INCORPORATED, OF NEW YORK, N. Y., A CORPORATION OF NEW YORK.

TELEPHONE SYSTEM.

Application filed May 15, 1924. Serial No. 713,428.

To all whom it may concern:

Be it known that I, LIPA POLINKOWSKY, a citizen of Russia, residing at 14 Rue du Bastian, in the city of Antwerp, Belgium, 5 have invented certain new and useful Improvements in Telephone Systems, of which the following is a full, clear, concise, and exact description.

This invention relates to telephone exchange systems in which connections are established by machine switching equipment, and particularly to systems of this character which are provided for dealing with traffic of small exchanges.

15 An object of the invention is to improve the efficiency and simplify the method of operation of small local telephone exchanges.

In accordance with one feature of the invention, the connecting or link circuits used 20 in the establishment of the connections terminate in a plurality of selecting units having access to different groups of lines, and it is so arranged that the selection of a particular unit for the further extension 25 of a call is effected by means operating under the control of the calling party.

In the preferred arrangement, the links terminate in a plurality of final selector switches and the operating magnet of the 30 final selector switch having access to the group of lines in which the called line is located, is chosen by a group of relays selectively operated in accordance with the value of the first digit of the called subscriber's 35 line designation.

In accordance with another feature of the invention, the selection of a particular unit and the operation of the selected unit may be accomplished in response to the 40 setting of an auxiliary or register switch operating under the control of the calling party. The setting of the brushes of this register switch may determine which relays of the group of relays shall be operated to 45 connect up the operating magnet of a particular selecting unit.

According to a further feature, on the release of the connection various selecting units of a link are tested to determine 50 whether they are in normal position and, if not, they are restored to normal position before the link is freed. An arrangement is provided to insulate the brushes of the switch if release occurs before the con-

nection is established, so as to avoid interference with other calls. 55

These and other features of the invention will be fully understood from the following description taken in connection with the drawings, in which one cord circuit in 60 accordance with this invention is shown diagrammatically.

In the drawings, a subscriber's circuit and a link circuit arranged in accordance with this invention are diagrammatically illustrated. Fig. 1 shows the line of a calling subscriber, a line finder switch, and a part of a link or connecting circuit. Fig. 2 shows the remainder of the link or connecting circuit with its associated register 70 switch, and also two of a number of final selector switches which may be adapted for completing a connection with a called subscriber's line. 75

The calling line 101 is provided with the usual line and cut-off relays while the link circuit consists of a line finder switch 102 for making connection with the calling subscriber's line and a plurality of final selector switches in which the link circuit terminates, two of which, designated 204 and 205, are shown. Each final selector switch is provided with two sets of brushes such as 206 and 207 for switch 204, and 209 and 210 for switch 205, either of which set in 85 the selected switch may be connected to the link circuit, depending upon the energized or deenergized condition of a connecting relay 212. 80

In the particular arrangement shown in 90 the drawings, each link circuit terminates in seven final selector switches and each final selector switch has associated therewith a stepping magnet 218, 219, 220, 221, 222, 223 or 224 which is enabled to step the 95 brushes of a final selector switch over the contacts in the banks thereof. Preferably, each final selector switch has fifty sets of contacts arranged in a complete circle, the final selector switches having a simple 100 selecting movement in one direction only.

In order to control the selection of a particular final selector switch, a register switch 217 consisting of the brushes 213, 214, 215 and 216 which are stepped over the 105 contacts in the bank by means of the stepping magnet 225, is provided. The brushes when in normal positions are arranged to

rest on the first contacts of their respective banks, as shown in the drawing, but these contacts will be hereinafter considered as normal contacts and the successive contacts 5 engaged by the brushes after said brushes have left their normal positions will be known as the first, second, third, etc., contacts. The setting of the brush 216 of the register switch for the first or hundreds 10 digit, determines which relay or relays of the group of relays 226 to 229 is or are energized to connect up the particular stepping magnet 219 to 224. After the relay or relays energized have locked up, the 15 register switch brushes are returned to normal position to render the register switch available for the next or tens digit.

The group of contacts engaged by the brush 214 of the register switch determines 20 the particular group of tens contacts, one of which will be selected for the units digit. The first and second contacts engaged by the brush 214 are connected together and to the first contact engaged by a test brush 208 25 of the selected final selector switch (assuming that switch 204 is selected), the third and fourth contacts are likewise connected together and to the eleventh contact engaged by the test brush, and in like manner, 30 the fifth and sixth, the seventh and eighth and the ninth and tenth contacts are connected together and to every tenth contact thereafter, such as the 21st, 31st, and 41st contacts, respectively. In this way the setting of the brush 214 places a selectable 35 potential on the first, the 11th, the 21st, the 31st or the 41st contact engaged by the brush 208, these contacts being the first contacts of the group of tens among which 40 the final selector switches may select the desired line.

It is arranged that immediately the brush 214 has operated for the tens digit, the stepping magnet of the final selector switch 45 is operated to step the brushes of the final selector switch until the brush 208 engages the contact connected up by the brush 214. Immediately this selecting operation has been accomplished, the brushes of the register switch are restored to normal so that 50 they may be again moved for the impulses representing the units digit and the brush 213 connects a particular contact engaged by the brush 208. When the brushes of the final selector switch are moved and the brush 208 comes in contact with the contact 55 connected by the brush 213, the brushes of the final selector switch are brought to rest in engagement with contacts of the desired line. The selection of a particular set of 60 brushes of the selecting unit is determined by the setting of the brush 215 of the register switch in accordance with the tens digit. If this digit is odd, the relay 212 is 65 operated and the upper set of brushes 206

is used, while if this digit is even, the relay 70 remains deenergized and the lower set of brushes 207 extend the connection.

The sequence switch disclosed in the Reynolds and Baldwin Patent No. 1,127,808, 75 of February 9, 1915, the contacts of which are shown in the drawings and controlled by the power magnet 103 are each closed in the positions indicated by the small numerals located at the particular contacts. 75

The system illustrated has a total capacity of 700 lines. If only 90 substations are connected, the relays 226 to 229 and all the stepping magnets, excepting the stepping magnet 218 associated with the first 80 selecting unit may be omitted. The capacity of the exchange may be adapted to the number of subscribers' lines connected by omitting one or more of the relays 226 to 229 and stepping magnets 219 to 224. 85

The selecting unit may be readily adapted for extending a connection to an idle line of a group of lines, or a private branch exchange by providing a relay 105, the relation of which is hereinafter more particularly described. Further, as the groups of lines may be small in number, the group hunting may be confined to a particular final selector switch 204 and may be carried out in only certain hundreds and for this 90 purpose the relay 105 which controls the group hunting is controlled by the group of relays 226 to 229 connecting a stepping magnet associated with a final selector switch. 100

This invention will be best understood by tracing the establishment of a call from one subscriber to another.

Establishment of connection.

When a calling subscriber at the subscriber's station 101 desires a connection with another subscriber's station, the removal of the receiver from the hook causes the calling subscriber's line relay 106 to operate from battery through the winding of relay 106, inner left contact of cut-off relay 107, ring side of the calling line, through the subscriber's substation apparatus, back over the tip side of the calling line, contact and outer left armature of relay 107, to ground. The line relay 106 connects the left hand winding of the cut-off relay 107 to the test terminal of the calling line which test terminal is therefore engaged by the test brush *d* of the line finder 102. The connection of the winding of the cut-off relay to this test terminal serves to place a selectable potential upon this terminal, thereby marking the line 101 as the calling 115 line. 120

Operation of line finder.

Upon the energization of line relay 106 a circuit is also closed for the starting relay 125 130

108 of the line finder switches which have access to the calling line. This circuit may be traced from battery, through the winding of relay 108, contact of relay 109, to ground at the left contact of line relay 106. The relay 108, upon energizing closes a number of circuits, one of which for the particular line finder illustrated in the drawing, may be traced from battery, through the winding of stepping magnet 110, the armature and contact thereof, outer left armature and contact of relay 108, lower left contact of cam 111 of the associated sequence switch, conductor 112, back contact of relay 113 to ground at the armature of relay 114. The stepping magnet 110 of the line finder switch 102 thereupon operates to rotate the brushes of the switch over the terminals in its bank and the stepping magnets of other switches 20 which have access to the group of lines in which the calling line is located are also energized in similar circuits closed by relay 108. When the calling line 101 is reached the cut-off relay 107 is energized in a circuit 25 which may be traced from battery, through the left winding of relay 107, contact and right armature of relay 106, test terminal engaged by brush *d* of line finder switch 102, right contact of cam 115, conductor 116, right hand low resistance winding of test 30 relay 114, and through the left hand winding of this relay in series, contact of relay 108, upper left contact of cam 117 conductor 118 to ground through the normal contact 35 of relay 119. The test relay 114 energizes in this circuit and opens at its back contact the circuit herein before traced for the stepping magnet 110 of the line finder switch 102, thereby causing this stepping magnet to de- 40 energize and to bring the brushes to rest upon the terminals of the calling line. The relay 114, upon operating, closes a circuit for the lower winding of relay 119, from battery, lower winding of relay 119, upper contact 45 of cam 120, conductor 128 to ground at armature of relay 114. The relay 119 thereupon operates and opens at its normal contact the circuit of the high resistance left hand winding of test relay 114, but the circuit 50 of the right hand winding of test relay 114 is maintained closed from ground, through the inner bottom armature of relay 119, cam 121 and its upper right contact, right hand winding of relay 114, cam 115 and its right 55 contact, conductor 122, brush *d* of the line finder switch, right armature and contact of relay 106, through the left hand winding of relay 107 to battery. The inner bottom armature of relay 119 makes with its contact 60 before its normal contact breaks and the test relay 114 is so wound that it will be maintained operated over its right hand winding in circuit with the cut-off relay 107, but the test relay 114 will deenergize if there are 65 two test relays connected in parallel over

the same cut-off relay. This operation prevents a plurality of finder switches from simultaneously testing a calling line. If this should happen the test relays of all the switches will become deenergized and the circuit of the stepping magnet will be again closed, so as to step the brushes of these switches away from the calling line, which will be selected by a switch, the brushes of which subsequently engage the calling line 75 terminals.

The connection of the low resistance right hand winding of test relay 114 to the brush *d* of the line finder switch holds the calling line busy so no other test relay can become 80 energized in parallel therewith. Upon the operation of relay 119 the calling line 101 is extended through the two top armatures of this relay to the stepping relay 123. The outer bottom armature of relay 119 closes an operating circuit for the controlling magnet 103 of the sequence switch, which may be traced from battery, through the winding of magnet 103, cam 124, cam 125 and its 85 lower left contact to ground at outer bottom armature of relay 119. The magnet 103 thereupon operates to cause the sequence switch to be driven out of position 1 and to be moved under the control of master cam 124 into position 2. 90

The cut-off relay 107 has been operated when the brush *d* of line finder switch 102 engages the test terminal of the calling line and opens at its left inner armature the circuit of the line relay 106, so that line relay 106 is disconnected from the calling line and deenergizes, the line relay 106 on opening the contact at its left armature causes the starting relay 108 to deenergize and this relay by deenergizing opens the circuit of the stepping magnet of the line finder switches previously set in motion so that these switches are brought to rest. 100

The stepping relay 123 is now under control of the dial switch of the substation 101. The relay 123 energizes as previously described, in series with the calling line and closes at its contact and left armature a circuit for the slow-to-release relay 126. The relay 126 upon operating closes at its contact before the sequence switch has reached position 2, and thereby maintains a circuit closed from the test brush *d* of the line finder switch, conductor 122, contact of relay 126, left contact of cam 115, conductor 116, right hand low resistance winding of test relay 114, conductor 127, upper right contact of cam 121, inner bottom armature of relay 119 to ground thereby maintaining 115 the calling line busy. 120

Before the sequence switch has reached position 2, the lower left contact of cam 120 was closed in position 1 $\frac{1}{2}$ whereupon a circuit is closed for the left hand winding of relay 113 from battery, through its winding, 130

- lower left contact of cam 120, conductor 128 to ground at armature of relay 114. Simultaneously a circuit is closed for the right hand winding of relay 113, which may be traced from battery, lower right contact of cam 129, conductor 149, cam 130 and its upper contact (closed in position 15 $\frac{1}{2}$), brush 213 in normal position, of the register switch 217 controlled by the register stepping magnet 225, conductor 131, right hand winding of relay 113 to ground. The relay 113 upon operating closes a locking circuit for itself which may be traced from battery, left hand winding of relay 113, lower right and left contacts of cam 132, inner left armature and contact of relay 113, lower right and upper right contacts of cam 133, brush 216 of the register switch in the normal position, conductor 134, to ground through low resistance winding in the dial tone relay 135. The test relay 114 is maintained energized in position 2 of the sequence switch from a circuit which may be traced from battery, through both windings of relay 107, contact and right armature of relay 107, brush *d* of the line finder switch 102, conductor 122, armature and contact of relay 126, left contact of cam 115, conductor 116, right hand winding of relay 114, conductor 127, upper right contact of cam 121, inner bottom armature and contact of relay 119 to ground.

The dialing tone is now transmitted to the calling line through conductor 136, lower left contact of cam 137, cam 138 and its lower left contact, through the condenser 177, outer top armature and contact of relay 119, brush "a" of the line finder switch, over the tip side of the line 101, through the subscriber's loop to the ring side of the line, brush *b*, contact and inner top armature of relay 119 to battery through the winding of relay 123. The calling subscriber 101 upon hearing the dialing tone knows that he may commence dialing the digits representing the designation of the desired line.

Transmission of hundreds digit.

The transmission of impulses for the first, that is the hundreds digit of the calling line causes the stepping relay 123 to be deenergized a number of times in accordance with the value of the digit dialed, and this relay upon deenergizing closes a circuit for the stepping magnet 225 of the register switch, the brushes of which are designated 213, 214, 215 and 216. The circuit for stepping magnet 225 may be traced from battery, through the winding of magnet 225, through the winding relay 139, contact and right armature of relay 123, back contact and armature of relay 140, upper right contact of cam 141 to ground. The opening of the contact at the armature of relay 123 has no effect upon the relay 126, as this relay being slow to release maintains its armature energized

during the transmission of the impulses. The stepping magnet 225, however, responds to the impulses and steps the brushes 213, 214, 215 and 216 a number of steps corresponding to the number of impulses received. The relay 139 which is located in the circuit of the stepping magnet 225 is arranged to be slow to release and is accordingly operated upon the transmission of the first impulses and retains its armature attracted until after the last impulse has been transmitted. The relay 139 closes an alternative circuit for the left hand winding of relay 113, thereby maintaining this relay energized after the register switch leaves its normal position. This circuit is necessary as otherwise the relay 113 would deenergize immediately the brush 216 of the register switch leaves its normal position. In position 2 of the sequence switch the left hand winding of the relay 113 has connected in parallel therewith a non-inductive resistance 142, this circuit being traceable from the left hand winding of the relay 113, conductor 143, upper left contact of cam 144, cam 129, resistance 142 to battery. This non-inductive resistance is provided in order to reduce the self-induction of the left hand winding of relay 113 as this is necessary when calls are extended automatically by the dialing of the digit 0 of the main exchange.

At the end of the dialing of the first digit, the relay 139 deenergizes, while the stepping magnet brings the brushes 213, 214, 215 and 216 to rest upon a particular set of terminals in the bank of the switch, corresponding to the value of the first digit dialed and the subsequent selection of the particular connecting circuit to be used in setting up the connection depends upon the terminals engaged by the brush of the register switch. If the brushes are moved one step, the brush 216 will engage the first contact, which is left dead, no connection being taken therefrom and the relay 113 thereupon deenergized as the locking circuit previously traced for this relay is now open at the brush 216 of the register, while the circuit closed by the relay 139 at its contact and armature for maintaining the relay operated is now opened due to the deenergization of relay 139. The relay 113 deenergizing, closes at its back contact and outer left armature a circuit for the sequence switch magnet 103 which may be traced from battery, through the winding of magnet 103, cam 124, cam 125 and its upper right contact, back contact and outer left armature of relay 113, upper right contact of cam 145, cam 141 to ground. The sequence switch thereupon operates and moves out of position 2 and then under the control of this master cam 124, into position 3 where it comes to rest.

If, instead of the digit 1, the digit 2

had been dialed for the hundreds digit, the brushes of the register switch are stepped into engagement with the second contact in the bank of the switch. In this position a 5 circuit is closed for the relay 226, in series with the winding of the relay 113, so that the relay 113 is prevented from deenergizing at this stage. This circuit may be traced from battery, left hand winding of relay 10, 113, lower right and lower left contacts of cam 132, inner left armature and contact of relay 113, lower right and upper right contacts of cam 133, brush 216 and the second contact in the bank engaged thereby, top 15 winding of relay 226 to ground. The relay 226 upon operating closes a circuit from battery, resistance 142, cam 129 and its lower left contact, conductor 146, contact and inner bottom armature of relay 226, top winding of relay 226 to ground, which circuit shunts the left hand winding of relay 113. The relay 113 thereupon deenergizes and closes a circuit as before explained, for the 20 sequence switch magnet 103, thereby driving 25 the sequence switch into position 3. The relay 226, upon operating disconnects at its back contact and inner top armature the stopping magnet 218 associated with the first 30 connecting unit and substitutes therefor the stepping magnet 219 associated with the second connecting unit, which stepping magnet is connected from battery, through the winding of magnet 219, back contact and inner top armature of relay 227, front contact and 35 inner top armature of relay 226.

If the digit 3 has been dialed for the hundreds digit, the brushes of the register switch are moved so as to engage the third contact in their banks, and in this position a circuit 40 is closed for the relay 227 which may be traced from battery, through left hand winding of relay 113, lower right and lower left contacts of cam 132, inner left armature and contact of relay 113, lower right and upper right contacts of cam 133, brush 216 of register switch, the third contact engaged thereby, top winding of relay 227 to ground. The relay 227 renders effective the stepping 45 magnet 220 of the next switch.

If it is desired to extend the capacity of the exchange beyond 400 lines, thereby necessitating the provision of more than four groups of connecting units, the relays 228 and 229 will be provided and these relays 50 would be operated in positions 5, 6 and 7 of the brush 216 of the register switch to connect up one of the stepping magnets 222, 223 and 224, this operation being similar to that described for the selection of the stepping magnets 218 to 221 and it is not thought necessary to describe this selection 55 in detail.

Should it be desired to extend the connection to the operator at the attendant switchboard, the calling subscriber will dial the 60

one digit 0, thereby setting the brushes of the register switch to the last set of terminals in the bank of the switch. As the sequence switch is now in position 2, a circuit is closed for maintaining the relay 113 70 operated from battery, through the winding of relay 113, lower right and lower left contacts of cam 132, left inner armature and contact of relay 113, lower right and upper right contacts of cam 133, brush 216 of the 75 register switch in position 10, brush *c* of the line finder switch 102 through the lamp 147 at the attendant switchboard to ground. The relay 113 remains operated and the sequence switch of the connecting unit remains in position 2 until the local connection is released in a manner to be herein-after described.

After the dialing of the hundreds digit and the passing of the sequence switch from 80 position 2 into position 3, as hereinbefore described in the establishment of a local connection, the test relay 114 is disconnected as its circuit is opened at the upper right contact of cam 121, when this contact leaves 85 position 2½ and in place of the relay 114, the relay 148 is connected in a circuit which may be traced from battery, through both windings of relay 107 and its contact and right armature, brush *d* and the line finder switch 90 102, armature and contact of relay 126, through the winding of relay 148, lower right contact of cam 121, inner bottom armature and contact of relay 119 to ground. In 95 order to be sure that the relay 119 is maintained operated during the interval between the deenergization of relay 114 and the energization of relay 148, the circuit is closed during the passing of the sequence switch through position 2½, for the relay 119 100 which may be traced from battery, through both windings of relay 119, upper left contact of cam 121, inner bottom armature and contact of relay 119 to ground, but when the relay 148 operates the upper winding of relay 119 is connected directly to ground at bottom armature of relay 148, so as to maintain the relay 119 operated. The relay 148 upon 105 operating, prepares a through connection from the calling line to the brushes of a final selector switch 204, the selection of the particular set of brushes to be used being hereinafter described.

When the sequence switch reaches position 110 3, a circuit is closed for restoring the register switch back to its normal position. This is effected by closing a circuit over the stepping magnet 225 of the register switch 115 through the self-interrupting action of its armature and contact so that when the circuit is closed, the magnet operates automatically to step the brushes from the position in which they were set by the dialing of the hundreds digit until these brushes 120 reach normal position, when the circuit is 125 130

opened and the stepping operation stopped. The circuit for the stepping magnet may be traced from battery, through the winding of magnet 225, contact and armature of the 5 magnet, upper right contact of cam 111, back contact and inner right armature of relay 113 to ground at armature of relay 114. When the brushes reach normal position a 10 circuit is closed from battery, through resistance 142, cam 129, conductor 149, cam 130 and its lower contact, brush 214 on the normal contact of the register switch, conductor 150, lower right contact of cam 151, conductor 152, both windings of relay 114, 15 upper left contact of cam 145 to ground at cam 141. The test relay 114 operates immediately this circuit is closed and opens the circuit hereinbefore traced for the stepping magnet 225 of the registering switch. 20 The test relay 114 upon operating, closes a circuit for the sequence switch extending from battery, through winding of magnet 103, master cam 124, cam 125 and its upper right contact, back contact and outer 25 left armature of relay 113, lower right contact of cam 120, conductor 128 to ground at armature of relay 114.

The sequence switch is driven out of position 3 and into position 4 where it comes 30 to rest. In passing from position 3 to position 4, the relay 113 operates in a circuit traced from battery, through left hand winding of relay 113, lower left contact of cam 120, conductor 128 to ground at armature of relay 114. The relay 113 is held operated in a circuit from battery, through left hand winding of relay 113, lower right and lower left contacts of cam 132, inner left 35 armature and contact of relay 113, lower right and upper left contacts of cam 133, brush 215 of the register switch in normal position to ground. A locking circuit is also provided for the right hand winding of relay 113, and this may be traced from ground through the right hand winding of relay 113, upper left and upper right contacts of cam 138, front contact and outer left armature of relay 113, conductor 157, lower left contact of cam 144, conductor 149, 40 cam 129 to battery through resistance 142, but the right hand winding of the relay 113 remains short circuited from ground at armature of relay 114, front contact of this relay, cam 120 and its lower right contact, conductor 157, and thence to battery through resistance 142 over the path hereinbefore 45 traced.

Transmission of tens digit.

50 The calling subscriber now transmits the impulses representing the second, or tens, digit of the called line designation. This digit determines the position in the bank of the selected final selector switches 204, 205, etc., from which the wipers will move

for the units digit. A final selector switch has fifty contacts in its bank, thus having five groups of ten contacts. The circuits of the switch are so arranged that the wipers are moved automatically to the first terminal of a particular group of terminals, which group is determined by the value of the tens digit. This operation is effected by the setting of the register switch controlled by the stepping magnet 225. This switch, as previously described, is restored to normal at the end of the series of impulses representing the hundreds digit, and is now stepped from normal in response to the tens digit. The contacts in the final selector switch over which the test brush 208 (assuming that switch 204 is selected) sweeps, are connected to the contacts of the register switch 217 engaged by the brush 214 in the following manner: The first and second contacts of the register are strapped together and connected to terminal No. 1 in a final selector switch bank engaged by brush 208. The third and fourth contacts of the register switch bank are connected together and to terminal No. 11 of the final selector switch. The fifth and sixth contacts are connected in a similar manner to terminal 21. The seventh and eighth to terminal 31 and the ninth and tenth to terminal 41.

95 It is arranged that immediately the impulses are received for the setting of the register switch, the brushes of the final selector switch are moved automatically from rest into engagement with a contact connected up by the brush 214 of the register. Thus, if the register switch receives one or two impulses for the second, or tens, digit, the brushes of the selected final selector switch are stepped one step so as to bring the brush 208 into engagement with the first contact. If the brush 214 is moved into engagement with the third or fourth contact, the brushes of the final selector switch will be moved into engagement with the eleventh contact in the bank and so on.

100 When the calling subscriber dials the tens digit, the relay 123 is deenergized a number of times, corresponding to the value of the digit and the circuit of the stepping magnet 225 of the register switch is closed at each deenergization of the relay in a circuit hereinbefore traced for the dialing of the hundreds digit, it being remembered that the sequence switch is now in position 4. 105 The operation of the slow-to-release relay 139 causes a circuit to be closed for the left winding of relay 113, thereby maintaining this relay operated after the register switch has left its normal position, as otherwise the circuit of this winding would be opened at the normal contact connected by the brush 215 of the register, this circuit being traceable from battery through left winding of relay 113, lower right and lower left con-

120

125

130

tact of cam 132, inner left armature and contact of relay 113, lower right and upper left contacts of cam 133, brush 215 in normal position to ground. As soon as the register switch has moved from its normal position, the test relay 114 is deenergized, the circuit from battery through the resistance 142, cam 129 and its lower left contact, cam 130 and its lower right contact, brush 214 5 on its normal contact, conductor 150, lower right contact of cam 151, conductor 152, both windings of relay 114, upper left contact of cam 145 to ground at cam 141, being opened when the brush 214 is moved 10 from normal position.

A circuit is now closed for the stepping magnet of the final selector switch associated with the particular connecting unit to be used. This circuit may be traced from 20 battery through the winding of magnet 218 (assuming that the connecting unit with which this magnet is associated has been selected), the armature and contact associated therewith, back contact and outer top armature of relay 229, back contact and armature of relay 228, back contact and outer top armature of relay 227, back contact and inner top armature of relay 226, lower right and upper left contacts of cam 153, front 25 contact and inner right armature of relay 113 to ground at the armature of relay 114.

This circuit causes the stepping magnet to operate automatically to step the brushes of the switch with which it is associated 30 from normal and these brushes will now move until brush 208 thereof comes into engagement with a contact connected up by the setting of the brush 214 of the register switch. The test relay 114 is now connected to the brush 208 of the final selector switch so that the test relay serves to test the contacts over which brushes 208 move and to stop the final selector when brush 208 reaches the contacts connected by the brush 40 214 of the register. The circuit of the test relay 114 is traceable from brush 208, outer right armature and contact of relay 113, upper left contact of cam 151, conductor 152, both windings of relay 114, upper left 45 contact of cam 145, cam 141 to ground. When the brush 208 of the final selector switch reaches contact 1 (assuming the register switch to have been moved one or two steps for the tens digit), the circuit of the 50 test relay is completed as hereinbefore traced to the brush 208 and thence over the first contact of the bank engaged thereby, contacts 1 or 2 engaged by brush 214 of the register switch, lower right contact of cam 130, cam 144 and its upper left contact, conductor 143, left winding of relay 113 to battery. The test relay 114 is energized 55 and by attracting its armature opens the circuit of the stepping magnet 218 at its con-

tact, thus bringing the brushes of the final selector switch to rest.

If the digits 3 and 4 had been dialed for the tens digit, the brushes of the final selector switch would have been moved another ten steps into engagement with the eleventh set of contacts in this bank. It may be arranged that the brushes of the final selector switch are stepped at a rate approximately equal to that of the brushes of the register switch so that the operation 75 of the final selector switch is finished practically at the same moment that the brushes of the register are brought to rest.

At the end of the tens series of impulses, the relay 139 deenergizes and if the brush 80 208 of the final selector switch has not reached the terminal connected up by the brush 214 of the register, the relay 113 will be maintained operated in odd positions of the switch in series with relay 212 and in 85 even positions of the switch through relay 105.

Assuming that the brushes of the register have been set to an odd position, the circuit maintaining the relay 113 may be traced 90 from battery through the left winding of relay 113, lower right and lower left contacts of cam 132, inner left armature and contact of relay 113, lower right and upper left contacts of cam 133, odd contact engaged by brush 215 of the register switch, lower winding of relay 212, conductors 154 and 155, lower right contact of cam 141 to ground. Relay 212 thereupon becomes energized, and closes a locking circuit for 100 itself at its contact and inner bottom armature through its upper low resistance winding, and this connection serves as a short circuit for the left winding of relay 113. Relay 113, however, is maintained energized 105 through its right hand winding until the brushes of the final selector switch have reached the position determined by the setting of the register switch. The circuit of the right hand winding of relay 113 may be traced from ground through the right hand winding of relay 113, upper left and upper right contacts of cam 138, front contact and outer left armature of relay 113, conductor 157, lower left contact of cam 144, cam 129 110 and its lower right contact to battery through resistance 142. When brush 208 of the final selector switch reaches the terminals connected up by the register switch, the test relay 114 is operated in the circuit hereinbefore described over the test brush 208, conductor 156, outer right armature and contact of relay 113, upper left contact of cam 151, conductor 152, both windings of relay 114, upper left contact of cam 145, cam 141 to ground. The relay 114 short circuits the 115 right winding of relay 113 at the front contact and armature of relay 114 so that both

120

125

windings of relay 113 are short circuited and the latter relay deenergizes causing the subsequent release of relay 114. A circuit is now closed through the back contacts of 5 relays 113 and 114 for restoring the register switch to normal position, this circuit being traceable from battery through the winding of relay 225, associated armature and contact, conductor 158, upper right contact of 10 cam 111, back contact and inner right armature of relay 113 to ground at the armature of relay 114. The register switch is thereupon restored to normal position and when 15 this is reached the test relay 114 is operated in a circuit from ground at cam 141, cam 145 and its upper left contact, both windings of 20 relay 114, cam 151 and its lower right contact, brush 214 in its normal position, lower right contact of cam 130, conductor 149, cam 25 129 to battery. The test relay 114 operates and opens at its back contact and armature the circuit hereinbefore traced for the stepping magnet 225 of the register switch so that the brushes of the latter are brought to rest in normal position.

The test relay 114 upon operating closes a circuit for the power magnet 103 of the sequence switch, this circuit being traceable from battery, magnet 103, master cam 124, 30 cam 125 and its upper right contact, back contact and outer left armature of relay 113, lower right contact of cam 120, conductor 128, front contact and armature of relay 114 to ground. The sequence switch moves 35 from position 4 into position 5 where it comes to rest. The right winding of relay 113 receives current from battery, cam 129, conductor 149, cam 130 and its upper contact, brush 213 of the register switch in 40 normal position, conductor 131 to ground through the right winding of relay 113, while the left winding during the movement of the sequence switch between positions 4 and 5, also receives current from battery through the left winding of relay 113, 45 lower left and lower right contacts of cam 120, outer left armature and back contact of relay 113, upper right contact of cam 125, cam 124 to ground. Relay 113 therefore operates quickly.

The apparatus is now in condition for receiving the units impulses from the calling station. These impulses set the register switch and the stepping magnet of the selected final selector switch operates to move the brushes of the final switch into engagement with a set of contacts marked by the register.

60 *Transmission of unit impulses.*

The final selector switch is set for the units digit in a manner similar to the setting for the tens digit. Upon the transmission of the units digit the stepping relay

123 deenergizes a number of times in accordance with the value of the digit and a circuit is closed for the stepping magnet 225 of the register switch as hereinbefore traced for the dialing of the hundreds digit. The magnet 225 thereupon operates to step the 65 brushes of the register switch from normal position to a position corresponding to the value of the units digit. The relay 139 energizes in series with the stepping magnet 225 upon the first impulses and maintains 70 its armature attracted until after the last units impulse has been transmitted. At its contact and armature the relay 139 maintains the relay 113 energized after the register switch has left normal position. After 75 the units impulses have been transmitted the relay 139 deenergizes whereupon the relay 113 also deenergizes as the circuits hereinbefore traced through the windings of the relay 113 are now both open. A circuit is 80 thereupon established for the stepping magnet of the selected final selector switch, this circuit being traceable from battery, through the winding of magnet 218 (assuming magnet 218 to have been selected), back contact 85 and outer top armature of relay 229, back contact and top armature of relay 228, back contact and outer top armature of relay 227, back contact and inner top armature of 90 relay 226, lower right and upper right contacts of cam 153, back contact and inner right armature of relay 113 to ground at 95 armature of relay 114. As soon as the brush 208 of the final selector switch has been 100 moved into engagement with a contact which has been connected by the brush 213 of the register switch in response to the dialing of the units impulse, a circuit is closed for the test relay 114 from ground at cam 141, cam 145 and its upper left contact, both windings 105 of relay 114, cam 151 and its upper right contact, brush 208 and contact engaged thereby, brush 213 of the register, upper contact of cam 130, conductor 149, cam 129 to battery. The test relay 114 thereupon 110 energizes and opens the circuit of the stepping magnet 218 of the final selector switch, so that this stepping magnet deenergizes and the brushes of the final selector switch are brought to rest on the contacts 115 of the desired line. The test relay upon energizing closes a circuit hereinbefore traced for the sequence switch 103. The sequence switch thereupon moves from position 5 into 120 position 6.

When the units digit is zero the brushes of the selector switch are not advanced for this digit, but remain on the set of terminals to which they are moved, as determined by the setting of the register switch for the tens digit. The test relay 114 is now operated in a circuit over the brush 213 and the tenth contact engaged thereby. This circuit may

be traced from battery, cam 129, conductor 149, cam 130, and its upper contact, brush 213 engaged with contact zero, conductor 150, lower right contact of cam 151, conductor 152, both windings of relay 114, upper left contact of cam 145, cam 141 to ground. The test relay thereupon energizes and closes the circuit of the sequence switch 103 which then moves out of position 5 into position 6 and is driven into the latter position by the energization of the relay 140. The relay 140 is energized in a circuit from battery, cam 129, conductor 149, cam 130 and its upper contact, brush 213 and the tenth contact engaged thereby, lower left and lower right contacts of cam 159, conductor 160, right hand winding of relay 140 to ground. The relay 140 energizes and closes a circuit for the sequence switch from battery, magnet 103, cam 124, cam 125 and its lower right contact, conductor 161, back contact and middle left armature of relay 105, front contact and armature of relay 140, lower left and upper right contacts of cam 153, back contact and inner right armature of relay 113 to ground at the armature of relay 114, as the test relay 114 deenergized as soon as the sequence switch left position 5. The sequence switch now moves into position 6 and from this point the connection proceeds in the manner described.

In position 6 of the sequence switch test relay 114 is used for testing the busy or idle condition of the desired line. The test circuit may be traced from either of the test brushes (bottom brushes of brush sets 206 and 207) according to whether or not the relay 212 has been operated, as determined by the value of the tens digit, that is, whether this digit is odd or even, thence through the operated or normal contacts at the outer bottom armature of relay 212, lower left contact of cam 151, conductor 152, both windings of relay 114, upper left contact of cam 145 to ground at cam 141. If the called line is found to be busy, the test relay 114 does not energize and as the circuit of this relay is opened at the upper left contact of cam 145, when the sequence switch moves to position 7 as hereinafter described, the test relay remains deenergized when the sequence switch reaches this position. The relay 140 is energized in a circuit from ground, right hand winding of relay 140, upper right and upper left contacts of cam 137, conductor 156, brush 208, brush 213 of the register switch, upper contact of cam 130, conductor 149, cam 129 to battery through resistance 142. The relay 140 thereupon energizes and closes a circuit hereinbefore traced for the sequence switch which thereupon moves from position 6 into position 7. In this position, if the test relay deenergized in position 6 indicating that the called line is busy, a busy tone

is transmitted to the calling line from the busy tone transformer 164 over a circuit from ground, through the transformer 164, lower right contact of cam 137, cam 138 and its lower left contact, through the calling 70 subscriber's loop and right hand winding of relay 123 to battery, and the subscriber is therefore notified that the called line is busy.

If the called line is found to be free, the test relay 114 is energized over the circuit 75 hereinbefore traced and through the cut-off relay 107 of the called line. The relay 114 closes at its front contact, a circuit for the relay 113 from battery, through the left hand winding of relay 113, lower left contact of cam 120, conductor 128 to ground at armature of relay 114. The relay 113 upon operating closes a circuit from ground through cam 141, cam 145 and its lower right contact, contact and inner left armature of relay 113, lower left and upper left contacts of cam 132, through the right hand winding of relay 114, cam 151 and its lower left contact, conductor 230, normal contact at relay 212, (it being assumed that relay 212 is deenergized), bottom brush (sleeve) of brush set 207 thence to the test contact of the calling line. This connection through the low resistance right hand winding of the test relay 114 maintains the called line busy. 95 As hereinbefore described, the test relay 114 is a marginal relay and should two final selector switches come to rest simultaneously upon the contacts of a line, the test relay would deenergize as it is unable to maintain its armature attracted when connected with the two cut-off relays in parallel. When the called line is found to be free, the sequence switch 103 upon reaching position 7 is maintained energized over the circuit 100 hereinbefore traced.

The sequence switch moves into position 8 where it comes to rest.

Group hunting.

The final selector switches may be readily adapted for extending connections to free lines of a private branch exchange group or groups. For this purpose the group hunting relay 105 is connected so as to be energized in response to the dialing of a particular even tens digit. As group hunting may only be desired on certain hundreds groups, the circuit of the relay 105 is also arranged to be controlled by the relays 226, 227, 228 and 229 controlling the selection of a particular selecting magnet 218 to 224 associated with a particular final selector switch of the link circuit. Thus in the particular arrangement shown in the drawing, the relay 105 is connected to the second contact engaged by brush 215 of the register switch and the circuit of the relay is taken through the outer top armature of relay 226 to ground at the outer bottom armature of 115 120 125 130

relay 227. Thus, in this particular arrangement shown in the drawings, group hunting may only take place in the first hundreds, that is, when both the relays 226 and 227 are deenergized, and further this group hunting is only effected when the tens digit is 2. It will, of course, be obvious that any other arrangement may be effected by a suitable connection to the circuit of the relay 105 with respect to the relays 226 to 229, and also with respect to the contacts engaged by the brush 215 of the register.

If the calling subscriber desires to extend a connection to a group of private branch exchange lines, he will dial the digit 1 for the hundreds digit and the digit 2 for the tens digit. After the dialing of the tens digit, a circuit is closed for the relays 113 and 105 from ground at outer bottom armature of relay 227, back contact and outer top armature of relay 226, through winding of relay 105, second contact engaged by brush 215 of the register switch, upper left and lower right contacts of cam 133 (it being assumed that the sequence switch is in position 4), contact and inner left armature of relay 113, lower left and lower right contacts of cam 132, through the left hand winding of relay 113 to battery. This circuit maintains the relay 113 energized and operates the relay 105. The relay 105, upon operating, closes its right armature and locking circuit for itself which may be traced from battery, through the resistance 142, cam 129 and its lower left contact, right armature, contact and winding of relay 105, conductor 166, outer top armature and contact of relay 226, outer bottom armature of relay 227 to ground. A portion of the above traced circuit through the low resistance 142 to the winding of the relay 105 acts as a short circuit for the left hand winding of the relay 113, so that the relay 113 now deenergizes. The relay 105 also opens at its outer left armature a circuit of the low resistance left hand winding of the relay 140 to ground so that this relay is now made quick acting. The relay 105 also changes the connections of the contacts and armatures of the relay 140 so as to enable this relay to control the operations of a final selector switch during group hunting.

In position 6 of the sequence switch, the relay 140 becomes energized as hereinbefore described, over the brush 208 of the final selector switch, its circuit being traceable over brush 208, upper left and upper right contacts of cam 137, through the right hand winding of relay 140 to ground. After brushes of the final selector switch have been set upon the first contact of the group of the private branch exchange lines, the test relay 114 tests this first contact from the bottom brush of brush set 207, this circuit being traceable from the bottom brush of set

207, normal contact of relay 212 (assuming 212 is deenergized), conductor 230, lower left contact of cam 151, conductor 152, both windings of relay 114, upper left contact of cam 145 to ground at cam 141. If this first line of the private branch exchange group is busy, the relay 114 does not operate, and a circuit is closed from ground over the back contact of relay 114, inner right armature and back contact of relay 113, over the stepping magnet 225 of the register switch, which circuit may be traced from battery, through the winding of magnet 225, the contact and armature of magnet 225, conductor 158, upper right hand contact (cut for position 6, but not shown) of cam 111, conductor 112, back contact and inner right armature of relay 113 to ground at armature of relay 114. The stepping magnet 225 now operates automatically to step the brushes of the register switch one step from the contacts into engagement with which they were set in response to the units digit. The circuit of the relay 140 is now opened at the brush 208 of the final selector switch as this brush 90 is no longer connected to a contact of the register switch by the brush 213 of the latter. The relay 140 releases its armature and closes a circuit for the stepping magnet 218 of the selected final selector switch which 95 may be traced from battery, through the winding of the stepping magnet 218, back contact and outer top armature of relay 229, back contact and top armature of relay 228, back contact and outer top armature of relay 227, back contact and inner top armature of relay 226, upper left and upper right contacts of cam 167, inner left armature and contact of relay 105, back contact and armature of relay 140, lower left and upper right contacts of cam 153, back contact and inner right armature of relay 113 to ground at armature of relay 114.

The stepping magnet 218 of the final selector switch moves the brushes of the latter one step into engagement with the next set of contacts of the private branch exchange. In this position the test relay 114 tests again. If this second line of the private branch exchange is free, the relay 114 is operated. If, however, it is busy, the relay 114 remains deenergized and the operation hereinbefore described is repeated until a free line or the last line of the private branch exchange group is reached.

If all the lines of the private branch exchange group are found busy and the final selector switch reaches the last terminal of the group, the test relay 114 becomes energized in a circuit over this last terminal, which is connected to a cam (not shown) cut for positions 12 and 12 1/4, conductor 149, cam 129 to battery. The test relay closes a circuit for driving the sequence switch out of position 6 into position 7.

When the sequence switch leaves position 6 the contact of the cam just mentioned is opened and the test relay 114 and the relay 113 are deenergized and the sequence switch 5 comes to rest in position 7, in which position a busy tone is transmitted in the manner hereinbefore described in the calling substation.

10 *Ringing of called subscriber.*

The called line having been tested and found free, ringing of the called subscriber is accomplished in position 8 of the sequence switch. In this position the low resistance 15 right hand winding of the test relay 114 is connected to ground independently of relay 113 through the upper right contact of cam 121, inner bottom armature and contact of relay 119 to ground, so that the calling line 20 is kept busy in case selection is advanced to this stage before release takes place. A circuit is closed for starting the ringing apparatus through the upper left contact of cam 169, this circuit being traceable from 25 battery, through resistance 142, cam 129, conductor 149, cam 169 and its upper left contact, through the winding of starting relay 168 of the ringing apparatus to ground, the ringing current is now transmitted to the 30 called line from the source of ringing current through the ringing interrupter 104 over conductor 170, lower left and upper right contacts of cam 171, contact and inner top armature of relay 148, inner top armature and back contact of relay 212 (assuming 212 to be deenergized), middle brush of 35 brush set 207, thence through the called line and back to the top brush of set 207, back contact and outer top armature of relay 212, outer top armature and contact of relay 148, lower right contact of cam 138, conductor 40 172, cam 137 and its upper right contact through the right hand winding of ringing cut-off relay 140 to ground.

45 As the relay 105 is deenergized in position 8 of the sequence switch, the left hand winding of relay 140 of low resistance is short circuited and this has the effect of making the relay slow acting so that it is 50 not energized by the normal ringing current flowing therethrough over the circuit just traced. When, however, the receiver at the called station is removed from the hook upon the response of the called subscriber, this relay is energized, whereby a circuit is 55 closed for the sequence switch which may be traced from battery, through the winding of magnet 103, cam 124, cam 125 and its lower right contact, conductor 161, back contact and middle left armature of relay 105, front contact and armature of relay 140, upper right contact of relay 141 to ground. The sequence switch moves out of position 60 8 into position 9. In position 9, the talking

circuit is completed through from the call- 65 ing subscriber to the called subscriber.

Release of the connection.

The release of the apparatus is under the control of the calling subscriber. At the end 70 of the conversation, when the calling subscriber hangs up, the stepping relay 123 deenergizes, whereby the circuit of the slow acting relay 126 is opened, and this relay deenergizes. Relay 126 deenergizes and opens 75 the circuit of the cut-off relay 107, and the relay 148, both of which deenergize. The deenergization of the cut-off relay 107 frees the calling line while the relay 148 upon deenergizing opens the holding circuit of 80 the relay 119 at its bottom armature and contact so that the relay 119 deenergizes. The relay 119 upon deenergizing closes the circuit hereinbefore traced for the sequence 85 switch from battery, through the winding of magnet 103, cam 124, cam 125 and its upper left contact, contact and outer bottom armature of relay 119 to ground.

The sequence switch moves from position 9 into position 11. When the sequence 90 switch leaves position 9, the test relay 114 is disconnected at the lower left contact of cam 151 and over the cut-off relay of the called subscriber, whereupon this line is freed. A circuit is now closed through the winding of stepping magnet 225 of the register switch from battery, through the winding of magnet 225, the contact and armature of magnet 225, upper right contact of cam 111, back contact and inner right armature 95 of relay 113 to ground at armature of relay 114. The stepping magnet 225 thereupon operates to restore the brushes of the register switch to normal and when these brushes reach normal position a circuit is closed 100 from ground at cam 141, conductor 173, cam 145, and its upper left contact, both windings of relay 114, conductor 152, cam 151 and its lower right contact, normal contact engaged by the brush 214 of the register, 110 lower contact of cam 130, conductor 149, to battery at cam 129. The test relay 114 operates, opens the circuit hereinbefore traced for the stepping magnet 225, and closes a circuit also hereinbefore traced for the sequence switch. The sequence switch thereupon moves from position 11 into position 115 12.

Position 12 of the sequence switch is the position in which the stepping magnet 224, 120 (if such a magnet is provided and is off normal) is restored to normal position. In this position the relays 228 and 229 are energized in parallel from ground, through the upper windings of relays 228 and 229, conductors 231 and 232, upon contacts of cam 174, to battery at cam 129. Relays 228 and 229 thereupon operate and a circuit is 125

closed from the stepping magnet 224 through the winding of magnet 224, the armature and contact of magnet 224, front contact and inner top armature of relay 229, 5 front contact and top armature of relay 228, back contact and outer top armature of relay 227, back contact and inner top armature of relay 226, lower right and upper right contact of cam 153 (upper right contact being cut for position 12 but not shown), back contact and inner right armature of relay 113 to ground at armature of relay 114. The stepping magnet 224, thereupon operates to rotate the brushes of the final 15 selector switch of the unit with which it is associated back to normal position, and when this position is reached, a circuit is closed for the test relay 114 from ground at cam 141, conductor 173, cam 145 and its upper 20 left contact, through both windings of relay 114, conductor 152, cam 151 and its upper right contact, conductor 156, test brush (similar to brush 208) of one of the seven final selector switches (not shown, but hereinbefore mentioned) and which switch is controlled by stepping magnet 224, normal contact in associated switch bank, a contact and cam (also not shown) cut for positions 12 and 12½, conductor 149 to battery at cam 25 129. The test relay 114 operates in this circuit and closes the circuit of the sequence switch which thereupon moves from position 12 to position 13.

If, however, a circuit is provided with a 35 stepping magnet such as 224, and the brushes controlled by the stepping magnet are in normal position when the release takes place, the relay 114 becomes energized immediately the release is initiated over the 40 circuit hereinbefore traced. The relays 228 and 229 become energized in a circuit which includes their upper windings in parallel, through the conductors 231 and 232 to battery at cam 129 as hereinbefore traced. Position 45 13 is the position in which the stepping magnet 223 (if provided and if off normal) is restored to normal position. In position 13, the relay 229 only is energized in a circuit from ground, upper winding of relay 229, conductor 231, upper left contact of cam 174, cam 129 to battery. The relay 229 operates and closes a circuit for the stepping magnet 223 from battery through the winding of magnet 223, armature and contact of magnet 223, front contact and outer 50 top armature of relay 229, back contact and armature of relay 228 (it being remembered that 228 deenergized when sequence switch moved from position 12), back contact and outer top armature of relay 227, back contact and inner top armature of relay 226, lower right and upper right contacts of cam 153, back contact and inner 55 right armature of relay 113 to ground at

armature of relay 114. The stepping magnet operates to restore the brushes associated therewith to normal position when the test brush (similar to 208) of the set of brushes (not shown) controlled by the stepping magnet 223 is in normal position, a circuit is closed for the test relay 114 from ground at cam 141, conductor 173, cam 145 and its upper left contact, both windings of test relay 114, conductor 152, cam 151 and its upper right contact, conductor 162, test brush (not shown, but similar to 208) controlled by stepping magnet 223, normal contact in the associated switch bank hence connected to a cam (also not shown) cut for positions 13 and 13½, conductor 149 to battery at cam 129. The test relay energizes and opens a circuit hereinbefore traced for the stepping magnet 223 so as to bring the brushes associated therewith to rest and closes the circuit for the sequence switch which thereupon moves to position 14.

In position 14 the relay 228 is energized through its upper winding from ground, conductor 232, upper right contact of cam 174, cam 129 to battery. Relay 228 upon operating closes the circuit of the stepping magnet 222 if the brushes controlled by this magnet are off normal, this circuit being traced from battery through the winding of magnet 222, the associated armature and contact, back contact and inner top armature of relay 229, front contact and top armature of relay 228, back contact and outer top armature of relay 227, back contact and inner top armature of relay 226, lower right and upper right contacts of cam 153 (upper right contact cut for position 14, but not shown), back contact and inner right armature of relay 113 to ground at back contact and armature of relay 114. The stepping magnet 222 thereupon operates to step the brushes associated therewith back to normal and when this normal position is reached, the test relay 114 energizes in a circuit from ground at cam 141, cam 145 and its upper left contact, through both windings of relay 114, conductor 152, cam 151 and its upper right contact, conductor 156, test brush (not shown, but similar to 208) controlled by stepping magnet 222, normal contact in associated switch bank, hence connected to a cam (also not shown) cut for position 14 and 14½, conductor 149 to battery cam 129. The test relay 114 operates, opens a circuit of the stepping magnet 222, and closes the circuit of the sequence switch which now moves from position 14 to position 15 where it comes to rest.

In position 15, both relays 226 and 227 are energized through their upper windings in parallel conductors 234 and 233, the upper right and upper left contacts of cam

129 to battery. These relays thereupon operate and connect the stepping magnet 221 from battery through the winding of magnet 221, armature and contact of relay 221, 5 front contacts and inner top armatures of relays 227 and 226, lower right and upper right contacts of cam 153 (upper right contact being cut for position 15, but not shown), back contact and inner right armature of relay 113 to ground at armature of relay 114. The stepping magnet 221 rotates the brushes associated therewith if off normal back to normal position when a circuit is closed for the test relay 114 over the 10 test brush (similar to 208) of the set of brushes (not shown) associated with the stepping magnet 221, normal contact engaged thereby, hence connected to a contact of a cam, (not shown) cut for positions 14 $\frac{3}{4}$ and 15 $\frac{1}{4}$. The test relay operates, opens 15 the circuit of the stepping magnet 221 and closes the circuit for the sequence switch which moves from position 15 into position 16. In position 16 only the relay 227 is 20 energized from ground, through the upper winding of relay 227, upper left contact of cam 129, to battery. The relay 227 connects up the stepping magnet 220 and if the brushes associated with this switch are off 25 normal this magnet is operated to move these brushes back to normal position and when this position is reached the test relay 114 is energized in a circuit including the test brush (similar to 208) of the set of 30 brushes (not shown) associated with the stepping magnet 220, normal contact engaged by this brush, hence connected to a cam (not shown) cut for positions 15 $\frac{3}{4}$ and 16 $\frac{1}{4}$. The test relay upon operating opens 35 the circuit of the stepping magnet 220 and closes the circuit of the sequence switch so 40 that the sequence switch moves from position 16 into position 17.

In position 17, the relay 226 only is energized over a circuit from ground, winding of relay 226, conductor 234, upper right 45 contact of cam 129 to battery, and the stepping magnet 219 is energized through the front contact and inner top armature of relay 226. The stepping magnet will operate 50 to rotate the brushes associated therewith if off normal back to normal position and when this position is reached, the test relay 114 is energized over the test brush 211 associated with this stepping magnet and normal contact engaged thereby, hence connected to a cam (not shown) cut for positions 16 $\frac{3}{4}$ and 17 $\frac{1}{4}$ so that the test relay 55 upon energizing opens the circuit of the stepping magnet 219 and closes the circuit of the sequence switch to move it from position 17 to position 18.

In this position the relay 226 is de- 60 energized and the stepping magnet 218 is energized through the normal contacts at

the upper armatures of relay 229, 228, 227 and 226 so that the stepping magnet 218 operates to stop the brushes associated therewith, if off normal, back to normal position and when this position is reached the 70 test relay 114 is energized over the test brush 208 and normal contact engaged thereby, hence connected as shown in the drawing, upper right contact of cam 144 cut for positions 17 $\frac{3}{4}$ and 18 $\frac{1}{4}$. The test relay 75 opens the circuit of the stepping magnet 218 bringing the brushes to rest in normal position and closes the circuit of the sequence switch so as to move the sequence switch from position 18 into position 1 which is 80 the normal position.

System including two digits.

In the system described and illustrated in 85 the drawing, it has been necessary to transmit three digits in order to obtain the called subscriber. If, however, the capacity of the system has not yet been extended beyond one hundred lines, it may be readily arranged 90 that only two digits are necessary for establishing the desired connection.

This is accomplished by causing the sequence switch to pass positions 2 and 3 and to move into position 4 in which the 95 dialing tone is given. For this purpose the upper right contact of cam 133 is shown connected to the brush 216 of the register switch. The relays 226 to 229 and the stepping magnet 219 to 224 are omitted. When, therefore, the sequence switch moves out of position 1, as before described, the relay 113 will be energized in a circuit from battery through the left hand winding of relay 113, 100 lower left contact of cam 120 cut for position 15 $\frac{1}{2}$, conductor 128, front contact and armature of relay 114 to ground. The locking circuit of relay 113, however, extending from battery, through its left-hand winding, lower right and lower left contacts of cam 132, inner left armature and contact of 105 relay 113, lower right and upper right contacts of cam 133, is open at the latter contact as hereinbefore described, so that the relay 113 deenergizes and closes the circuit 110 for the sequence switch from battery through the winding of magnet 103, cam 124, cam 125 and its upper right contact, back contact and outer left armature of relay 113, upper right contact of cam 145, conductor 173 to ground at cam 141. The sequence switch 115 thereupon moves to position 3. In this position the relay 114 is operated from battery, cam 129, conductor 149, cam 130 and its lower contact, brush 214 of the register switch in normal position, lower right contact of cam 151, conductor 152, through both windings of relay 114, upper left contact of cam 145, conductor 173, to ground at 120 cam 141. The sequence switch 125 thereupon moves to position 4. In this position the relay 114 is operated from battery, cam 129, conductor 149, cam 130 and its lower contact, brush 214 of the register switch in normal position, lower right contact of cam 151, conductor 152, through both windings of relay 114, upper left contact of cam 145, conductor 173, to ground at 125 cam 141.

The test relay 114 thereupon operates and 130

closes a circuit of the sequence switch from battery through the winding of magnet 103, cam 124, cam 125 and its upper right contact, back contact and outer left armature 5 of relay 113, lower right contact of cam 120, conductor 128 to ground at armature of relay 114. The sequence switch thereupon moves to position 4 and in this position, it is arranged to transmit the usual dialing tone 10 to the calling subscriber through the conductor 136 and the lower right and upper left contacts of cam 171. The starting circuit of the dialing tone apparatus is now connected by way of the upper left contact 15 of cam 133 and brush 215 on its normal contact to ground.

The starting circuit for the dialing tone apparatus may now be traced from battery, through the left hand winding of relay 113, 20 lower left contacts of cam 132, inner left armature and contact of relay 113, lower right and upper right contacts of cam 133 (the upper right contact would in this case be cut for position 4), brush 216 of the register switch in normal position, conductor 134 to ground through the winding of starting relay 135. The calling subscriber upon hearing the dialing tone will now transmit the digit representing the number of the 25 called subscriber's line, the first digit being the tens digit and operating in the manner hereinbefore described to cause the stepping magnet 225 of the register switch to set its brushes to a predetermined position. The 30 register switch is restored to normal position immediately the brushes of the first unit associated with the stepping magnet 218 are set to the first set of contacts of the tens group in which the line of the called subscriber is located. The second digit which 35 is the unit digit, again sets the register to cause the brushes of the unit to be moved to the contacts of the called subscriber's line. In this way, the hundreds digit which 40 in the circuit hereinbefore described selects a stepping magnet associated with a particular unit of the final selector switch is omitted, the first digit transmitted being the tens which, in the manner hereinbefore described, 45 effects the setting of the brushes of the first unit.

If the calling subscriber dials a designation which does not exist, a hundreds digit would in this case be either 8 or 9 and the 50 brush 216 of the register would be set to either the eighth or ninth contact. The relay 113 now remains operated in position 2 of the sequence switch in a circuit from battery, through the left hand winding of 55 relay 113, lower right and lower left contacts of cam 132, inner left armature and contact of relay 113, lower right and upper right contacts of cam 133, brush 216 of the register switch, conductor 160, through the right hand winding of relay 140 to ground. The

operation of the relay 113 prevents the closure of the sequence switch circuit while the circuit of the stepping magnet 225 is open at its back contact and armature of relay 140. The sequence switch is thus prevented 70 from moving from position 2 until the calling subscriber hangs up his receiver to release the connection.

What is claimed is:

1. In a telephone system, subscribers' lines 75 arranged in groups, a plurality of separately operable selective switches each having access to a different group of said lines, a single link circuit terminating in all of said switches, a register individual to said link circuit, and means controlled by said register for selecting one of said switches and for operating the selected switch to extend said link circuit to one of the subscribers' lines. 85

2. In a telephone system, subscribers' lines arranged in groups, a plurality of selective switches, a separate propelling means for driving each of said switches, each of said switches having access to a different group 90 of said lines, a single link circuit terminating in all of said switches, a register connected to said link circuit, and means controlled by said register for selecting one of said switches and for operating the selected switch to extend said link circuit to one of the subscribers' lines. 95

3. In a telephone system, subscribers' lines arranged in groups, a plurality of selective switches each having a separate stepping magnet for operating the same and each having access to a different group of said lines, a single link circuit terminating in all of said switches, a register for extending said link circuit to any of said switches, and means controlled by said register for selecting one of said switches and for operating the stepping magnet to extend said link circuit to one of said subscribers' lines. 100

4. In a telephone system, subscribers' lines arranged in groups, a plurality of selective switches, a separate propelling means for driving each of said switches, each of said switches having access to a different group 105 of lines, a single link circuit terminating in all of said switches, and a register individual to said link circuit, responsive to one series of pulses to select one of said switches and responsive to other series to connect the selected switch to one of said subscribers' lines. 110

5. In a telephone system, subscribers' lines arranged in groups, a plurality of selective switches, a stepping magnet for operating each of said selective switches, a single link circuit terminating in all of said switches, a register individual to said link circuit, a group of relays for selecting one of said stepping magnets, and means controlled by 120 said register for variably operating said re- 125

lays to cause said magnet to step one of said selective switches into engagement with one of said subscribers' lines.

6. In a telephone system, a plurality of groups of subscriber's lines, a link circuit, a plurality of selective switches in which said link circuit terminates, each of said selective switches adapted to extend a connection to a line of one of said groups, and means operable upon the release of said connection to

test said selective switches in order to determine whether they are in normal positions, and said means being also operable if said selective switches are found in off-normal positions to restore them to normal positions before said link circuit is released. ¹⁵

In witness whereof, I hereunto subscribe my name this 29th day of April A. D., 1924.

LIPA POLINKOWSKY.
